United States Patent Office

Des. 225,449
Patented Dec. 12, 1972

225,449

TABLE LIGHTER

Gotz Florian Strzelczyk, Bad Homburg, Germany, assignor to Rowenta-Werke GmbH, Offenbach am Main, Germany

Filed Jan. 4, 1971, Ser. No. 103,953

Term of patent 14 years

Int. Cl. D27—05

U.S. Cl. D48—27

Fig. 1.

Fig. 2.

Fig. 3.

Fig. 4.

Fig. 5.

FIG. 1 is a perspective view of a table lighter showing my new design;

FIG. 2 is a top plan view thereof on an enlarged scale;

FIG. 3 is a side elevational view thereof on an enlarged scale;

FIG. 4 is a rear elevational view thereof on an enlarged scale; and

FIG. 5 is a bottom plan view thereof on an enlarged scale.

I claim:

The ornamental design for a table lighter, as shown and described.
